US00D946862S

(12) United States Design Patent (10) Patent No.: US D946,862 S
(45) Date of Patent: * Mar. 29, 2022

(54) PET TREAT

(71) Applicant: Mars, Incorporated, McLean, VA (US)

(72) Inventors: Joanne Johansson, Batley (GB); Helena Skinn, Batley (GB); Joel Cockcroft, Batley (GB); Wayne Morris, Leeds (GB); Adam Smith, Barrie (CA); Keith Kristiansen, Stratford, CT (US); Roland Charriegz, Plattekill, NY (US); David Demar, Edgewater, NJ (US); Philip Ryan, Dublin (IE)

(73) Assignee: Mars, Incorporated, McLean, VA (US)

() Term: 15 Years

(21) Appl. No.: 29/802,025

(22) Filed: Aug. 2, 2021

Related U.S. Application Data

(60) Division of application No. 29/727,021, filed on Mar. 7, 2020, now Pat. No. Des. 928,451, which is a continuation of application No. 29/672,987, filed on Dec. 11, 2018, now Pat. No. Des. 880,809.
